UNITED STATES PATENT OFFICE.

EDWARD PEIRCE, OF OPPORTUNITY, WASHINGTON.

CHUTE.

Application filed April 12, 1921. Serial No. 460,718.

To all whom it may concern:

Be it known that I, EDWARD PEIRCE, a citizen of the United States, residing at Opportunity, in the county of Spokane and 5 State of Washington, have invented certain new and useful Improvements in Chutes, of which the following is a specification.

My present invention relates to improvements in chutes or gravity conveyers of the 10 wall type, adapted especially for transferring merchandise or other packages from an upper floor or level to a lower floor or level.

The primary object of the invention is the 15 provision of an appliance for use in storage houses or ware houses whereby packages may with convenience and dispatch be transferred or conveyed from one level to a lower level and there discharged, and in 20 carrying out this object I have utilized an appliance which is extremely simple in construction, comparatively inexpensive in cost of manufacture and installation, and durable. By the utilization of my invention 25 in its physical embodiment I am enabled to conserve or save space in the warehouse interior, and avoid the use of wells or openings in the building floors, as now customarily used, by locating the major portion 30 of the chute on the exterior of the warehouse, with the receiving and discharge ends of the chute opening in the interior of the warehouse. The structure of the chute provides a smooth, unobstructed path of travel 35 for the merchandise, and may be furnished with a braking or retarding portion for slowing up the travel of the package before it emerges from the discharge end of the chute or conveyer.

40 In the accompanying drawings I have illustrated one complete example of the physical embodiment of my invention adapted for transferring boxes of apples from one floor or level of a warehouse to a 45 lower floor, in which the parts are combined and arranged according to the best mode I have thus far devised for the practical application of the principles of my invention, and a modification of this form of the 50 invention is also illustrated in the drawings, wherein the chute is equipped with a specially formed portion forming a retarder adjacent to the discharge end of the chute.

Figure 1 is a view in side elevation of 55 the chute constructed according to my in-

vention, and combined with the side wall and floors of a storage or warehouse for the transfer of merchandise.

Figure 2 is a transverse sectional view 60 through the chute.

Figure 3 is an end view of the chute, with the spout or end extension removed.

Figure 4 is a front view of one of the 65 spouts or end extensions.

Figure 5 illustrates a modified form of 70 the invention.

In carrying out my invention I utilize the side wall 1 of the building or warehouse and the upper floor or level 2 and lower floor or level 3, as indicated in Figure 1, the 75 purpose of the appliance being to convey, by gravity, merchandise or other packages of goods from the upper level to the lower level, through the chute 4. As shown in Figure 1 the chute is a rigid structure having a curved outline, and hollow, preferably rectangular in cross section and made up of sheet metal plates forming the front and rear walls 5 and 5', and similar plates 6 and 6' forming the inner and outer sides of 80 the curved structure. The curved plates 6 6' are each fashioned with flanged edges 7, and at 8 these edges are riveted to the edges of the flat plates 5 and 5' as best seen in Figure 2.

The curved chute is located on the exterior of the building wall 1 with its ends extending through the wall, one above and the other below the floor 2, and the receiving spout 9 and discharging spout 10 are located inside the building or warehouse. The spouts are of duplicate construction and form extensions of the chute, the ends of the latter being fashioned with four flanges 11 by means of which the chute is attached 95 to the interior face of the building wall 1, while the spouts which are open at the rear, front and top are provided with three complementary, integral flanges 12, riveted at 13 to the flanges 11.

The spouts are made up of a single sheet or plate of metal with bent integral flanges suitably perforated for rivets, and preferably the front edge of the bottom of each spout is turned under as at 14 to present a 105 blunt edge and provide a brace or reinforcement for the receiving and discharging extensions of the chute.

The utility of the chute will be readily apparent, as it is obvious that the merchan- 110

dise, as boxes of apples may be placed on the receiving extension 9 and pushed into the orifice at the upper end of the chute, and the box will pass through the smooth and unobstructed passage within the chute and be discharged at the end or extension 10 in Figure 1, from where it may be transported as desired. Other chutes may be employed in conjunction with that illustrated, as for instance an upper chute may be utilized to convey the boxes to the floor marked 2, and a lower chute may have its receiving end adjacent the discharge end 10, and convey the boxes to a floor beneath the floor marked 3. In Figure 5 the chute 4' is illustrated in connection with the wall 1^a and equipped with receiving end or extension 9' and discharge extension 10'. As a means for retarding or braking the passage of the descending box I may utilize a depressed portion or pocket at 4^a adjacent to the outlet or discharge end of the chute. Due to friction in the lower wall of the pocket caused by the sharp turn in the depression the box will be slackened up in its movement, and the friction may be such as to retard the box so that its momentum will be sufficient only to discharge the box on the bottom of the ex-

tension or spout 10' without falling to the floor beneath the spout.

From the above description taken in connection with my drawings it will be evident that I have provided an appliance that fulfills the objects of my invention, and which will perform its functions as a comparatively perfect instrumentality for the purpose.

Claims:

1. The combination with a building wall and adjoining floors, of an outwardly curved, exterior casing forming a chute having its open, receiving and discharging ends, projecting through the building wall above said floors, a receiving extension on the upper end of the chute and a discharge extension on the lower end of the chute within the building.
2. The combination with a building wall and adjoining floors, of an outwardly curved, exterior casing forming a chute with interior openings, a receiving extension, a discharge extension, and said chute having a retarding depression adjacent the discharge end thereof.

In testimony whereof I affix my signature.

EDWARD PEIRCE.
